US00D653652S

(12) **United States Design Patent**
Kroyer

(10) **Patent No.:** **US D653,652 S**
(45) **Date of Patent:** **** Feb. 7, 2012**

(54) **LOUDSPEAKER**

(75) Inventor: **Kristian Kroyer, Hojbjerg (DK)**

(73) Assignee: **Libratone A/S, Skovlunde (DK)**

(**) Term: **14 Years**

(21) Appl. No.: **29/381,065**

(22) Filed: **Dec. 15, 2010**

(30) **Foreign Application Priority Data**

Jun. 16, 2010 (EP) 001720327-0001

(51) **LOC (9) Cl.** **14-01**

(52) **U.S. Cl.** **D14/214**

(58) **Field of Classification Search** D14/204, D14/210–216, 172; 181/143–144, 147–148, 181/150–153, 157, 198–199; 381/300–303, 381/306, 332–333, 336, 345, 361–364, 386–388

See application file for complete search history.
